(57) **CLAIM**

The ornamental design for a swordfish electronic lock interior escutcheon, as shown and described.

DESCRIPTION

FIG. 1 is an upper-left front perspective view of the swordfish electronic lock interior escutcheon.

FIG. 2 is a front view of the swordfish electronic lock interior escutcheon.

FIG. 3 is a right side view of the swordfish electronic lock interior escutcheon.

FIG. 4 is a left side view of the swordfish electronic lock interior escutcheon.

FIG. 5 is a top view of the swordfish electronic lock interior escutcheon; and,

FIG. 6 is a bottom view of the swordfish electronic lock interior escutcheon.

The broken lines are for the purpose of showing exemplary hardware associated with the swordfish electronic lock interior escutcheon, and they form no part of the claimed design.
